UNITED STATES PATENT OFFICE.

HAROLD B. DONLEY, OF COLUMBUS, OHIO, ASSIGNOR TO THE JOHN W. BROWN MFG. CO., OF COLUMBUS, OHIO, A CORPORATION OF OHIO.

VEHICLE HEAD LAMP.

Application filed December 27, 1926. Serial No. 157,124.

This invention relates to improvements in vehicle head lamps, or to lamps of the type comprising a casing having a reflector arranged therein with a light source in the form of an incandescent bulb adjustably disposed in front of the reflector. The principal object of the invention resides in the provision of a lamp having these general features of construction and wherein provision is made for a compound adjustment of the light source with the end in view of obtaining proper relationship between the focal point of the reflector and the light source, in order to control to better advantage the propagation of light from the lamp by well defined beams for illuminating specific zones and to prevent promiscuous scattering of the light into undesired zones or regions to the front of the lamp.

Another object of the invention rests in providing a lamp of the character aforesaid with a bulb support having an adjustable mounting by means of which the support, an incandescent bulb associated therewith may be moved axially and horizontally with respect to its associated reflector and, in addition, adjusted vertically or in a plane at right angles to the first named plane of adjustment, in order that the filament or filaments of the bulb may occupy proper operating relationship with respect to the associated reflector and to compensate for irregularities and variations in the manufacture of the bulb, the reflector and associated parts.

The invention is especially applicable in connection with the so called "double filament" type of lamp bulbs in that through the compound adjustment the several filaments of the bulb may be accurately and carefully positioned to operate in their intended way to the best advantage.

A further object of the invention rests in the provision of a construction of simple, readily operated, and inexpensive design which may be readily employed in connection with lamp parts of standard manufacturing design, and wherein the focal adjusting means for the lamp bulb will be mainly situated within the lamp casing to the rear of the reflector, with the actuating portions of the adjusting means arranged exteriorly of the casing to the rear of the latter, where they will be out of the way and will not inter-

fere with operations attending the cleaning of the lamp.

With these and other objects in view, as will appear as the description proceeds, the invention consists in the novel features of construction, combinations of elements and arrangements of parts hereinafter to be fully described and pointed out in the appended claim.

In the accompanying drawing:

Figure 1 is a vertical sectional view taken through a vehicle head lamp and illustrating more particularly the focal adjusting means comprising the present invention.

Figure 2 is a vertical transverse sectional view on the line 2—2 of Figure 1.

Figure 3 is a horizontal sectional view illustrating in plan the mechanism disclosed in Figure 1.

Figure 4 is a transverse vertical sectional view on the line 4—4 of Figure 1.

Figure 5 is a sectional view setting forth a modified form of the lamp adjusting means.

Referring more particularly to the drawing there has been illustrated therein a lamp 1 of the type commonly employed in connection with motor vehicles, and while this type of lamp has been selected for purposes of description and illustration, nevertheless, it will be understood that the invention is not limited solely to lamps designed for vehicle illumination especially, but may be utilized in connection with electric lamps for any other purpose or use.

In this instance, however, the lamp comprises a casing 2, having the open end thereof covered by a lens 3 and a retaining ring 4. Within the casing there is disposed a standard form of reflector 5, facing toward the front of the lamp and provided with a relatively enlarged axially disposed opening 6.

Adjustably mounted within the opening 6 for movement both longitudinally and vertically with respect thereto is a bulb socket or support 7 which detachably carries in the usual manner a standard type of lamp bulb 8, which may be of either the single or double filament variety. Connected with one side of the support 7 is a rearwardly and longitudinally extending bar 9, which terminates at its inner end in a substantially U-shaped portion 10. This portion of the bar is provided with threaded openings for the reception of the threaded shank of an adjusting screw 11.

This screw is disposed axially of the casing and has its shank loosely received within an opening formed in the rear wall of the casing. The headed end 12 of the screw is disposed 5 exteriorly of the casing and is situated preferably in a depression 13 provided in the rear wall of said casing. The screw 11 is surrounded by a spring 14, which bears upon the U-shaped portion 10 of the bar and retains 10 the latter in its adjusted position upon the screw shank. It will be manifest that by rotating the screw 11 longitudinal travel will be imparted to the bar 9 and to the bulb support connected therewith, so that the lamp bulb may be adjusted longitudinally with respect to the principal axis of the reflector so as to vary the positions of the filament of the bulb with respect to the focal point of the reflector. 15

20 In order to provide for the lateral or transverse adjustment of the bulb support in addition to the axial adjustment described, there is mounted upon the inner wall of the casing 2, adjacent to the screw 11, a bracket 25 15 having an out-turned ear to which is pivoted as at 16 the inner end of a swinging arm 17. This arm extends substantially parallel to the bar 9, and has its outer end provided with a spring clip 18, which frictionally embraces the outer walls of the support 7. In addition, the arm 17, adjacent to its pivotal point, is provided with an offset crank portion 19, located below the plane of the screw 11. The crank portion is provided with a 30 laterally turned ear 20, provided with a threaded opening for the reception of the threaded shank of a second adjusting screw 21, arranged parallel to and below the primary screw 11. A coil spring 22 is situated 35 between the ear 20 and the bracket 15 and serves to maintain the screw in its adjusted position. Lead wires 23 extend from the support 7 to the exterior of the lamp and lead to any suitable source of electrical energy. 40

45 In operation, it will be seen that by adjusting the main screw 11 the lamp bulb may be moved in and out for a substantially axial and horizontal direction. However, by adjusting the second screw 21 the arm 17 will be oscillated about its pivotal connection 16 and since the arm 17 carries the bulb support at its outer end, it follows that the oscillation of said arm will result in imparting corresponding movement to the bulb 8 so that the latter will be moved in this instance in a substantially vertical plane, or more broadly speaking, in a plane perpendicular to the plane of adjustment secured by the main screw 11. By this compound adjustment of the lamp bulb the latter may be 50 adjusted with accuracy and convenience to

occupy its most effective positions in front of the reflector so that the light beams emitted from the lamp may be more accurately controlled and vagrant or stray rays eliminated. 65 The adjustment operates with particular facility when the double filament type of bulb is used, enabling each filament of a bulb of this type to be properly positioned in the front of the reflector and an efficient operating 70 condition maintained. It will be understood that the screw 11 fits loosely within the opening provided therefor in the back of the casing and therefore readily adapts itself to the angular position secured by the actuation of 75 the second screw 21. The springs 14 and 22 serve to positively position the parts, to avoid loss of adjustment and to prevent noise or rattle between the relatively movable parts. In Figure 5 a slightly modified form of the invention has been illustrated wherein the arm 17^a does not have its outer end directly connected with the bulb support, but is provided with a laterally disposed pin 24, which is received within an elongated slot 25 provided 80 in the bar 9^a. The operation and principles of the construction are, however, similar in every respect to the construction set forth in describing the preferred form of the invention. It will be observed that the construction employed is simple and is yet efficient and reliable. The adjusting screws 21 are out of the way and to a large extent concealed and will not interfere with operations attending the cleaning of the lamp. 85

What is claimed is:

In a lamp, a casing, a reflector mounted within said casing and provided with an axial opening, a bulb support freely movable within said opening and adapted to carry an incandescent bulb in advance of said reflector, an adjusting screw disposed axially within said casing between said reflector and the back wall of the casing, a connecting member having the forward end thereof secured to said support and the rear end thereof provided with a threaded bearing for the reception of the threaded shank of said screw, spring means for retaining said screw in its positions of adjustment, a member pivotally mounted contiguous to the rear wall of said casing and in horizontal alignment with said screw, the outer end of said pivoted member being associated with said bulb support to swing the latter vertically, a second screw engaged with a threaded bearing carried by said pivoted member, and spring means for retaining said threaded screw in its various positions of adjustment. 100 105 110 115

In testimony whereof I affix my signature.

HAROLD B. DONLEY.
